UNITED STATES PATENT OFFICE.

ORA L. SAMS, OF LOS ANGELES, CALIFORNIA.

COIN-CONTROLLED ELECTRIC-FAN ATTACHMENT.

Application filed July 29, 1920. Serial No. 399,681.

To all whom it may concern:

Be it known that ORA L. SAMS, a citizen of the United States of America, residing at Los Angeles, in the county of Los Angeles 5 and State of California, have invented new and useful Improvements in Coin-Controlled Electric-Fan Attachments, of which the following is a specification.

The object of the invention is to provide 10 means for controlling the operation of a fan, particularly of the electric type to the end that by dropping a coin of the proper denomination in a chute provided for that purpose an operation of the fan for a 15 limited time will ensue whereupon the original or stop condition of the mechanism will be restored or the current discontinued until another coin is inserted to close the circuit or release the mechanism for further 20 operation, and furthermore to provide in this connection means whereby a plurality of coins of the proper denomination may be deposited in succession or series in the chute to be successively advanced into proper position 25 to maintain the circuit and the fan in operation for a multiple of the time or period prescribed for operation under the influence of a single coin; and with these objects in view the invention consists in the 30 construction and combination of parts of which a preferred embodiment is shown in the drawings, wherein:

Figure 1 is a side view of a fan equipped 35 with a coin controlled mechanism embodying the invention.

Figure 2 is a plan view of the coin controlled mechanism, the casing or housing of the same being omitted.

Figure 3 is a rear view showing the housing or casing partly broken away.

Figure 4 is a side view of the same.

Figure 5 is a detail view in perspective of the trip and resisting mechanism.

The apparatus is designed for use in connection with a fan 10 of any ordinary or commercial form or type, the housing or casing 11 which encloses the coin controlled mechanism being attached to the rear of the fan casing and including the front and rear 45 discs or plates 12 and 13 connected by suitable brace rods 14. A drive shaft 15 is mounted in suitable bearings in said discs or plates and is provided at its front end with a coupling for engagement with the arbor 50 of the fan motor indicated at 16 in Figure 4, said coupling in the construction illustrated

consisting of a threaded stem 17, and this drive shaft is connected by speed reducing gearing with a driven shaft 18, the speed reducing gearing in the construction illustrated consisting of a worm 19 on the drive shaft meshing with a worm gear 20 on an intermediate shaft 21, a worm 22 on the intermediate shaft meshing with a worm gear 23 on a second intermediate shaft 24, and a worm 25 on said second intermediate shaft meshing with a worm gear 26 on the driven shaft. It will be understood that any desired number of intermediate gears and shafts may be employed to provide for a 70 communication of motion from the drive shaft to the driven shaft at such speed as may be desired to the end that with a given rate of rotation of the drive shaft (controlled obviously by the fan motor) the 75 driven shaft may make one complete revolution during any preferred and predetermined period of time, as for example one hour.

In connection with the mechanism there 80 is employed a clutch which when the attachment is used in connection with a fan of the electric type consists of a circuit closer indicated generally at 27 and including the contact 28 and a switch 29 pivotally mounted at 30 and yieldingly actuated by a spring 31 to impel it to a circuit closing or operative position.

In connection with the clutch mechanism there is employed a trip lever 32 having a 90 catch 33 for engagement with the free end of a locking lever 34 pivoted at 35 and connected by a link 36 with the switch lever 29 to the end that when the switch lever is moving in a circuit opening direction motion is communicated from the link 36 to the locking lever 34 to arrange the free end of the latter in the path of engagement by the catch 33 of the trip lever. The trip lever is yieldingly actuated by a spring 37 95 adapted when the trip lever is released to move the latter, which is pivoted at 38 in the direction necessary to engage the locking lever, and said trip lever is provided with a coin seat 39 for contact with the edge 100 of a coin indicated in dotted lines at 40 to the end that said trip lever by the pressure of a coin is moved in the direction indicated by the arrow in Figure 3 to withdraw the catch 33 from engagement with the locking lever 34 to permit the switch lever 29 105 to close the circuit and thus permit the fan 110

to be operated. At the opposite side of the coin chute 41 there is arranged a coin check and supporting device 42 consisting of a rocking lever pivoted at 43 and having an ear 44 to support the opposite edge of the coin from that which bears upon the seat 39, said rocking lever being yieldingly held in its coin engaging position by a spring 44' and being adapted toward the end of a period of movement of the driven shaft 18 to be actuated by a pin 45 on said driven shaft to release the coin which has been holding the trip lever 32 repressed and permit it to drop into engagement with an ear 46. Obviously as soon as the pin 45 releases said checking lever it is returned to its normal position by the spring 44' and the coin is dropped out of the chute and the trip lever is released. Should there be another coin, however, behind the coin which was serving to hold the trip lever repressed, due to the fact that two or more coins have been deposited in the chute, the detention of the first coin by the ear 46 will serve to check the downward movement of the second coin, so that when the lever 42 is released to drop the first coin, the second coin will be retained in trip repressing position to insure the further operation of the mechanism for a second period of time represented by said second coin.

Carried by the driven shaft as for example by the worm gear 26 is a cam 47 in co-operative relation with which is a pin 48 carried by a release lever 49 having a rocking and sliding movement through a slot 50 thereof engaged with a pivot pin 51 and provided with an actuating spring 52. Said cam is provided with a seat or notch 53 designed for the reception of the pin 48 when the cam of which the motion is obviously controlled by the driven shaft makes one complete revolution and which complete revolution is made in the prescribed period of time for which the mechanism is set for operation under the control of one coin. Said release lever is provided at the opposite end from the actuating spring 52 with a pin 54 engaged with the slot 55 in a link 56 which is connected with the switch lever to the end that when the release bar is moved in the direction indicated by the arrow *a* in Figure 5 and in Figure 3 motion communicated thereby through the link 56 will raise the switch lever and open the circuit to cause the operation of the fan to cease.

The release lever carries a lateral arm 57 upon the extremity of which is mounted a dog 58, pivoted as at 59, and provided with a seat 60 disposed normally in the path of movement of the shifting pin 61 carried by and extending radially from the intermediate shaft 21. As this shaft turns and the shifting pin engages the seat or notch 60, the shifting lever 49 is rocked on the pin 51 as

a pivot with the result that the pin 48 is raised out of its seat or notch 53 to traverse the surface of the cam 47. The dog 58 at a point opposite the pivot 59 has a pin and slot connection 62 with the lateral arm 57 and this permits swinging movement of the dog sufficient to maintain it in operative connection with the pin 61 to enable the raising of the pin 48 out of the notch 53, the continued depression of the arm 57 due to the action of the pin 61 resulting in the final disengagement of the seat 60 from the pin and the resumption of the normal position of the dog 58 with reference to the arm.

When the fan is inactive the trip lever 32 is disposed with the catch 33 in obstructing relation with the end of the locking lever 34. The insertion of a coin in the chute, however, results in the lateral shifting of the trip lever in opposition to the spring 37 and the disengagement of the latch 33 from the locking lever 34, when the spring 31 is free to act and move the switch 29 into engagement with the contact 28, this operation not only placing the fan motor in circuit with the source of supply but moving the link 56 so that the pin 54 on the release lever, which pin is normally disposed in the bottom of the slot 55, passes to the top of said slot.

The rotation of the fan motor sets in operation the shaft 21 and the shaft 18, the former, because of the nature of the gearing, having a higher angle of velocity than the latter. The pin 61 at this time is brought into engagement with the seat 60 in the dog 58 and the release lever is rocked on the pin 51, as aforesaid, and the pin 48 released from the seat 53, the shaft 18 by this time being in motion and the cam 47 revolving in the direction indicated by the arrow in Figure 5. By the time the pin 48 shall have been released from the seat 53, the lateral arm 57 will have been depressed and, carrying with it the dog 58, the latter will be lowered to a point where the pin 61 may ride over the upper edge. The pin 48 therefor rests on the upper edge of the cam 47 and traverses said upper edge as the shaft 18 rotates, until finally it impacts with the edge of the dog 63 secured on the outer periphery of the cam 47 adjacent the seat 53. Longitudinal movement is then imparted to the release lever 49, the slot 50 permitting such movement. The pin 54 at this time being in the upper end of the slot 55 of the link 56, the latter is rocked on its pivotal connection with the switch 29 and moved into a position in substantial perpendicularity with the switch, rocking the latter on its pivotal connection and releasing it from the contact 28.

The advancement of the release lever 49 changes its position with respect to the pin 51 so that a pivotal or rocking point is provided at another point in the lever. The lateral arm 57 therefore will not be de-

pressed to the level to which it was originally depressed by the engagement of the pin 61 with the seat 60 and will consequently be in a position to again enable the engagement 5 of the seat 60 with the pin 61 so that it may be a second time rocked with the pin 51 in the remote end of the slot 50 from that which it formerly occupied, thus providing for the rocking of the release lever a second 10 time to raise it free of the dog 63 and to re-engage the seat 53. At this instant the pin 54 will be at the upper end of the slot 55 but on the reengagement of the pin 48 with the seat 53 and the subsequent sliding move- 15 ment of the cam 47 following, the spring 52 will operate to retract the release lever 49 when the pin 51 will be moved to the opposite end of the slot 53 and the pin 54 advanced to the bottom of the slot 55, thus 20 leaving the parts in position to be again actuated by a second slug or coin, the raising of the switch lever 29 being accompanied with a reengagement of the latch 33 with the locking lever 34.

25 Assuming that the operation of the release lever as above described has taken place, with the result of opening the switch 29 to break the circuit by which the fan motor is operated, the securing of the lock- 30 ing lever 34 by the catch 33 will occur as the coin is disengaged from the bearing seat 39 but if a second coin is located in the chute in following relation to the coin which has been holding the trip lever in its releasing 35 position, the repression of the trip lever will continue under the influence of the second coin, and therefore, as the release lever 49 is drawn back by its spring 52 upon the dis- 40 engagement of the pin 61 from the seat or notch 60 of the dog 58, the switch lever will again be free to return under the influence of its spring 31 to the circuit closing position so that the operation of the fan will 45 continue.

45 Having described the invention, what I claim as new and useful is:

1. A coin controlled stop mechanism for motor driven fans having driving and driven shafts connected by speed reducing 50 gearing, a switch lever yieldingly actuated for movement to its closed position, locking means connected with the switch lever for holding the latter in its inoperative position comprising a coin actuatable trip 55 for releasing the locking means, and mechanism for moving the switch lever to open position comprising a locking lever for said gearing mounted for rocking and longitudinal movement and connected to the 60 switch lever, means carried by said locking lever and an element carried by said gearing for imparting switch opening movement to said locking lever, and means for disengaging said locking lever from said gearing.

65 2. A coin controlled stop mechanism for

motor driven fans having driving and driven shafts connected by speed reducing gearing, a switch lever yieldingly connected for movement to its closed position, locking means connected with the switch lever for holding the latter in inoperative position and comprising a coin actuatable trip, a locking lever for said gearing mounted for rocking and longitudinal movement and operatively connected with the switch lever to move the latter to open position, a retracting spring connected with said locking lever, a cam actuatable by the driven shaft for imparting switch opening movement to the locking lever, and a pin and dog carried respectively by said locking lever and said gearing for releasing the locking lever from the cam upon completion of the switch opening movement of said locking lever.

3. A coin controlled stop mechanism for motor driven fans having driving and driven shafts connected by speed reducing gearing, a switch lever yieldingly connected for movement to its closed position, locking means connected with the switch lever for holding the latter in inoperative position and comprising a coin actuatable trip, a locking lever for said gearing mounted for rocking and longitudinal movement and operatively connected with the switch lever to move the latter to open position, a retracting spring connected with said locking lever, a cam actuatable by the driven shaft for imparting switch opening movement to the locking lever, and provided with a seat and with a dog adjacent to said seat, a pin carried by the locking lever for engagement in said seat and abutting engagement with said dog, and means for releasing said pin from said seat and from engagement with said dog, said means consisting of a dog and pin respectively carried by the locking lever and said gearing.

4. A coin controlled stop mechanism for motor driven fans having driving and driven shafts connected by speed reducing gearing, a switch lever yieldingly connected for movement to its closed position, locking means connected with the switch lever for holding the latter in inoperative position and comprising a coin actuatable trip, a locking lever for said gearing mounted for rocking and longitudinal movement and operatively connected with the switch lever to move the latter to open position, a retracting spring connected with said locking lever, a cam actuatable by the driven shaft for imparting switch opening movement to the locking lever and having a dog for engagement with the locking lever to impart switch opening movement to the same in opposition to the retracting spring, and tilting means for the locking lever consisting of a pin and dog carried respectively by the locking lever and said gearing.

5. A coin controlled stop mechanism for motor driven fans having driving and driven shafts connected by speed reducing gearing, a switch lever yieldingly connected for movement to its closed position, locking means connected with the switch lever for holding the latter in inoperative position and comprising a coin actuatable trip, a locking lever for said gearing mounted for 10 rocking and longitudinal movement and operatively connected with the switch lever to move the latter to open position, a re-

tracting spring connected with said locking lever, means carried by the driven shaft for imparting longitudinal movement to the locking lever to effect switch opening movement to the same, and cooperating means carried by the locking lever and the gearing to effect tilting movement of the lever to disengage it from said gearing. 15 20

In testimony whereof he affixes his signature.

ORA L. SAMS.
